UNITED STATES PATENT OFFICE.

WALTER KIESER, OF BERLIN, GERMANY, ASSIGNOR TO GENERAL ELECTRIC COMPANY,
A CORPORATION OF NEW YORK.

CENTRIFUGAL PUMP.

1,020,699.

Specification of Letters Patent. Patented Mar. 19, 1912.

Application filed January 12, 1909. Serial No. 471,978.

To all whom it may concern:

Be it known that I, WALTER KIESER, a citizen of Switzerland, residing at Berlin Germany, have invented certain new and useful Improvements in Centrifugal Pumps, of which the following is a specification.

This invention relates to centrifugal pumps in which the fluid to be pumped is driven by one or more rotating impellers, each of which receives fluid in a chamber concentric with the shaft by which it is rotated, and throws it out through orifices or nozzles in its periphery. In such pumps, it is common to produce an equalization of pressure between the two sides of the impeller wheel by means of a port in the interior wall of the wheel. This does not, however, perfectly equalize the pressure, because there still remains an axial thrust on the wheel.

The object of my invention is to provide an automatic equalization of the axial thrust.

In the accompanying drawings, Figure 1 is a side elevation of a turbine-driven centrifugal pump embodying my improvements; Fig. 2 is a vertical axial section of the pump proper; Fig. 3 is an enlarged section of one of the impellers; Fig. 4 is a similar section of a modified impeller; and Fig. 5 is an enlarged fragmentary section of another modification.

The pump 1 and its driving turbine 2 are mounted on a common pedestal 3 so as to constitute a self-contained unit. The shaft 4 may be common to both machines or it may be made in two parts and united by a coupling as shown. It is suitably journaled in bearings 5, 6, the former mounted on one end of the pedestal and the latter supported on the head of the pump. In the same journal-box 7 which contains the bearing 6 is a thrust bearing 8. The turbine overhangs the pedestal beyond the bearing 5, being preferably supported by a bracket 9 extending from the journal box 10. The pump is located at the other end of the pedestal, the lower half 11 of the pump casing being preferably cast integral with said pedestal. The upper half 12 of said casing meets the lower half on a horizontal axial plane. One head 13 is integral with the casing, while the other head 14 is removable and has a flange 15 by which it can be bolted to the casing. In each head is a

packing sleeve 16 and ducts 17 leading thereto by means of which sealing fluid may be admitted. Stuffing boxes 18 are provided for the shaft at each end of the pump.

The number of impellers 19 may be varied in different pumps, but in the one illustrated three are shown, mounted rigidly on the shaft inside the casing. The number of vanes or blades on each propeller may also be varied. By means of end rings 20 and diaphragms 21 each impeller is inclosed in its own chamber from which the nozzle or diffusing passage or passages 22 extend radially outward through the diaphragms. In the halves of the casing are circumferential grooves 23 for receiving the liquid flowing through said passages 22 and guiding it around the edges of the diaphragms into radial channels 24 in said diaphragms, through which the liquid is conveyed to the inlets 25 of the successive impellers.

By arranging the parts in the manner described the machining thereof is a very simple operation. Ordinarily the halves of the casing will be bolted together and each complete circumferential groove finished by the same machine operation or operations. Since the surfaces forming the groove or passage can be machined and thus made smooth the efficiency of the pump may be made high because of the fact that resistance to flow of the liquid being pumped will be a minimum. The liquid is fed to the inlet of the first impeller by a supply pipe 26 and issues from the last impeller and its surrounding nozzle into a delivery pipe 27.

The construction of the impeller is best shown in Fig. 3. The discharge portion 28 has parallel outer walls 29, 30 lying in planes perpendicular to the axis. The hub 95 has a series of steps formed by perpendicular and circumferential surfaces 31, 32. The walls of the chamber in which the impeller rotates are formed preferably by rings 33 let into suitable recesses in the end rings 100 and diaphragms, and they correspond in shape with the impeller, leaving a narrow clearance space between the several adjacent surfaces.

The path of the liquid is from the supply pipe 26 through the three impellers in series to the delivery pipe 27. The back pressure on the impellers sets up a thrust lengthwise of the shaft and toward the left in all the figures of the drawings. This thrust can be 110

partly relieved by the ports 34 which admit the pressure to the space between the impeller and the next diaphragm or the head 14. The sheet of liquid thrown out through the annular discharge portion of the impeller is received by the stationary diffuser, but the back pressure causes some of the liquid to flow laterally over the edge of the impeller into the clearance spaces between said impeller and the adjoining rings. If now the impeller shifts bodily toward one of said rings it is evident that the clearances between all cylindrical surfaces will remain unchanged, while those on one side of the impeller and between the surfaces perpendicular to the axis will decrease and those on the opposite side increase. Under normal conditions there are multiple leak paths for the fluid leaving the impeller, one right and one left, and the amount of fluid flowing through them depends upon the restriction or restrictions therein. Take the case of the structure in Fig. 3 for example and assume the impeller shifted to the left. The outlet for the leakage fluid on the left-hand side is decreased while the inlet remains the same, hence the pressure in the side chamber will build up and tend to thrust the impeller back to its normal and stable position. This action is assisted by the stepped construction of the impeller which affords a tortuous passage for the liquid tending to prevent it from escaping too freely, and forms a series of chambers in which the pressure can be built up. The condition of affairs on the right of the impeller is reversed, that is to say the inlet remains the same but the outlet area is increased due to the separation of the perpendicular surfaces and by such an amount as will cause the pressure of the leakage fluid in the side chamber to drop and thus in a negative way assist in re-establishing the proper balance of the impeller. It is to be observed also that the port 34 performs its function of equalizing pressures on opposite sides of the impeller in so far as possible.

In the modification shown in Fig. 4, the edge of the impeller is grooved circumferentially and receives the converging throat portion 35 on the diffuser, said throat being preferably made in a ring 36 clamped against the wall of the impeller chamber by the rings 33. This construction provides the impellers with lips 37 which are adapted to close toward or against one side or the other of the throat 35 as the impeller shifts to and fro. The rings 31 or their equivalent stationary elements are provided with grooves 38 which form chambers adjacent to the radial surfaces 31 of the hub adapted to retain a certain body of liquid at all times and thus equalize the flow of liquid from one chamber to the next. Assuming that the impeller shifts to the left

from any cause, the passage for fluid on the right of the nozzle is restricted by the lip and hence less fluid can flow, and since the outlet area between the circumferential surfaces at the stepped portion of the impeller is virtually the same, or at least is no smaller, the fluid pressure in the right hand side chamber will be less than before. On the left-hand side the conditions are reversed. The area of the outlet remains the same or virtually so while the inlet passage to the chamber on that side is considerably larger, hence the pressure in the lefthand side chamber or chambers will more nearly approach that of the fluid leaving the impeller, and since this pressure is superior to that on the opposite side of the impeller the latter will be shifted to the right and to its normal position where it is in a state of equilibrium. In connection with balancing the thrust on these impellers it is to be noted that the position of the shaft in its bearings will be determined by the joint action of all of the impellers, each impeller performing its share of the work, whatever that may be.

For certain pumps, I find it desirable to make the clearances between the cylindrical surfaces greater on one side than on the other. As an example I may use a clearance between annular surfaces on the right hand side of the impeller of .3 of a millimeter and on the left .25 of a millimeter. This arrangement is illustrated in a somewhat exaggerated manner in Fig. 4, and also in Fig. 5 as applied to the pump of the type shown in Fig. 3. By varying the clearances on one side or the other a certain definite thrust or bias may be created at all times which opposes the normal thrust due to the action of the fluid in the impellers.

If desired, the space or chamber at one or both sides of the nozzle may be widened, and a flange 39 located at the inner end to narrow the passage for the liquid into the grooves 38.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,

1. A centrifugal pump having an impeller provided with a stepped series of perpendicular and circumferential surfaces of revolution, and stationary elements having opposed surfaces arranged to give clearance spaces communicating on each side of the outlet with the delivery of the impeller so that the spaces between perpendicular surfaces will vary in width with the axial shifting of the impeller, and the balancing pres-

sure in said spaces will vary inversely with their width.

2. A centrifugal pump having an impeller provided with smooth lips on each side of its discharge portion, and having also steps on each side of said portion, a diffuser having a receiving portion entering between said lips, and stationary elements having grooved steps corresponding with the steps 10 on the impeller.

3. A centrifugal pump comprising a casting having inlet and discharge ports, an impeller located therein which receives the fluid to be pumped from one side, a port in 15 the body of the impeller to approximately balance the pressures exerted thereon, an auxiliary balancing means comprising parts located on each side of the impeller and having opposed perpendicular and circumferential surfaces of revolution arranged in a 20

stepped series, the said surfaces being separated by clearance spaces to which the fluid at the discharge pressure of the impeller has access, and a driving shaft.

4. A centrifugal pump having an impeller 25 provided with perpendicular and cylindrical surfaces of revolution, and stationary elements having opposed surfaces that communicate with the delivery of the impeller so that the clearance spaces between 30 perpendicular surfaces will vary in width with axial shifting of the impeller, the said cylindrical clearance spaces on one side of the impeller being greater than on the other.

In witness whereof, I have hereunto set 35 my hand this 23rd day of December, 1908.

WALTER KIESER.
